RAZOR BLADE SHARPENER

Joseph P. Egan, Long Branch, N. J.

Application March 15, 1934, Serial No. 715,757

1 Claim. (Cl. 30—25)

The object of my invention is to produce a simple device whereby used razor blades may be resharpened.

One form of this razor blade sharpener is illustrated in the accompanying drawing of which Figure 1 is a side view; Figure 2 a detailed, sectional view; Figure 3 a perspective sectional view.

The main feature of the invention is carried out in Figure 2. 1 is the body of the sharpener; 2 a shaft with left hand thread movable lengthwise by means of adjusting knob 3 rotating freely in part 1 but containing a nut 4 integral with part 3; 5 shows a blade in position for sharpening one side. The stop 6 supports blade against locking action of shaft 2 when tightened. 7 is the holder for the blade which has a V-shaped slot on either side for the purpose of conveniently inserting or removing the blade.

To insert razor blade, turn adjustment head 3 in a counterclockwise direction which withdraws shaft 2. Insert blade in holder, 7, allowing about $\frac{1}{2}$ " of blade to project out of the holder for sharpening. Secure blade in holder by turning adjustment head 3 in a clockwise direction.

Sharpen blade by drawing it diagonally across

leather strop or hone as is done with a straight razor.

Sharpen the other side of blade by releasing adjustment head 3, shift blade to opposite side without taking it from holder, letting blade protrude about $\frac{1}{2}$ ". Secure it by turning adjustment head 3 in a clockwise direction. Sharpen on leather strop or hone as explained above. Blade is then sharpened on both sides. Release by turning adjustment head 3 in a counterclockwise direction.

Having thus fully described my invention, what I claim as new and useful is:

A razor blade holder comprising a hollow body having a pair of aligned slots at one end for receiving the blade, a stop at said end adjacent to said slots, the other end of said body constituting a handle, a shaft movable lengthwise in said handle said shaft having a threaded portion and a blade engaging portion opposed to said stop for clamping a blade between them, and an adjusting knob mounted for free rotation at the end of the handle and having a threaded portion engaging the threads of the shaft to move said shaft lengthwise in order to clamp or release a blade.
